UNITED STATES PATENT OFFICE

2,466,551

FASTENER-APPLYING IMPLEMENT

Arthur H. Maynard, Warwick, R. I., assignor, by
mesne assignments, to Bostitch, Inc., a corpora-
tion of Rhode Island

Application August 17, 1945, Serial No. 610,961

8 Claims. (Cl. 1-3)

1

This invention relates to improvements in fastener-applying implements for attaching papers and other sheets, securing labels and tags to articles of commerce and use generally for stapling and stitching together various objects.

One object of the invention is to provide an implement of the type indicated which is more convenient to load with a supply of fasteners and easier to operate for the purposes specified.

Another object is to provide an implement of improved construction and arrangement capable of efficient operation and less subject to derangement and wear in its mechanism.

Another object is to provide an implement of the type indicated adapted for economical cost of manufacture and more durable for long periods of use.

Further objects of the improvement are set forth in the following specification which describes a preferred form of construction of the device as illustrated by the accompanying drawings. In the drawings:

Fig. 1 is a general view in perspective of the present improved fastener-applying implement;

Fig. 2 is an enlarged side elevation of the same;

Fig. 3 is a longitudinal sectional view thereof;

Fig. 4 is a side elevation of the implement similar to Fig. 2 showing the driver-operating lever or cover for the magazine as raised above the latter for loading it with fasteners such as U-shaped staples;

Fig. 5 is a transverse sectional view of the latching means for the cover taken on line 5-5 of Fig. 4;

Fig. 6 is a perspective view of the latch for retaining the driver-lever or cover in operative position relatively to the magazine-arm;

Fig. 7 is a perspective view of the shear-plate mounting which defines the rearward side of the throat in the magazine through which the fasteners are driven; and

Fig. 8 is an enlarged view of the forward part of the lever 5, part sectional in a median longitudinal plane and illustrating the latch and the means for mounting it in place on the lever.

Referring to the accompanying drawings, the present improvements are herein illustrated as applied to a fastener-applying implement for feeding and driving U-shaped staples, although they may also be used in devices for applying other types of fasteners.

The present implement comprises a base 2 provided with clinching means 3 at its forward end, a magazine-arm 4 for containing a supply of fasteners which is pivoted at the rearward

2

end of the base, and an operating lever 5 constituted as a cover for the top of the magazine in the arm 4.

The base 2 comprises two parts, a sheet-metal plate 6 formed with a protrusion or boss 7 at its forward end indented or recessed to form the clinching grooves 3 and vertical stanchions 10 at its rearward end folded upwardly at its sides. The metal plate is preferably supported on an ornamental rest or sub-base 11 constructed of plastic or the like, being received in a shallow recess 12 therein, see Fig. 3, shaped in conformity to its marginal outline. The plate 6 may be fastened to the rest 11 by means of a snap-fastener 15, shown in Fig. 3, to adapt the operative parts of the implement to be detached therefrom for use without the sub-base.

Hingedly mounted above the base 2 is the magazine-arm 4 which is of channel-shape with a bottom wall 18 and upstanding sides 19 for enclosing the fasteners or staples 5 resting on the bottom. The arm 4 is pivotally mounted at its rearward end between the stanchions 10 by means of a transverse pin 20 projecting through circular ears on the arm and stanchions. At its forward end the sides 19 of the arm 4 are folded inwardly in tabs 22 partly closing the end and forming the fore part of the throat through which the fasteners or staples 5 are driven.

The rearward wall of the throat 24 is provided by a shear-plate 25, so-called, shown in detail in Fig. 7, which is formed with rearwardly-extending legs 26 for mounting it within the sides 19 of the arm 4. Referring to Figs. 2, 3 and 7, the legs 26 are provided with lugs 27 at their lower edges inserted in slots in the bottom wall 18 and swaged or riveted over to fasten the shear-plate in position in spaced relation to the tabs 22 which cooperate therewith to form the narrow throat or guideway 24 for the staples 5. The forward ends of the legs 26 are recessed to form shoulders 28 which overlap and engage the end of the bottom wall 18 of the arm 4 to locate the shear-plate 25 in position; and the lugs 27 on the legs have concaved edges to assist the riveting operation which fastens the mounting in the arm. It will be understood that the legs 26 and the ends of the shear-plate 25 are spaced inwardly from the sides 19 of the arm 4 to permit the legs of the staples 5 to slide therebetween as they are fed forwardly in the magazine. As herein shown the shear-plate 25 is beveled from the center outwardly and downwardly across its upper edge to provide for sup-

porting crowned staples *s* having crossbars bowed or arched upwardly at the center.

A rod 30 having its reduced end held in a hole 31 in the shear-plate 25 extends rearwardly therefrom at the center of the arm 4 with its opposite end engaging a hole in an angular support 32 resting on the bottom 18 of the arm. The rearward end of the rod 30 engages against a reduced portion of the pivot pin 20 for retaining the pin from longitudinal displacement in the ears at the ends of the arm 4. The staples *s* are straddled across the rod 30 within the sides 19 of the arm 4 with the ends of their legs resting on the bottom 18.

A staple-pusher 33 of inverted channel shape having legs 34 resting on the bottom 18 of the arm 4 is provided with opposite holes through which the rod 30 extends to adapt the pusher to slide longitudinally thereof. Coiled around the rod 30 is a helical spring 35 tensioned between the rearward leg 34 of the pusher 33 and the member 32 to adapt it to slide the pusher forwardly for feeding the staples *s* toward the throat 24 at the forward end of the arm 4. The spring 35 also serves to hold the angular support 32 against the pin 20 to retain it in position.

The fastener-applying lever 5 which forms the closure for the open top of the magazine-arm 4 is of inverted channel-shape comprising a top 40 and depending sides 41. The rearward ends of the sides 41 of the lever 5 are formed with circular ears 42 which straddle the sides of the stanchions 10 on the plate 6 and are pierced with holes for receiving the ends of the pin 20 to pivotally mount the lever on the base 2. The lever 5 thus is adapted to rock on its pivot toward and away from the base 2 and also relatively to the magazine-arm 4 with its sides 41 enclosing the sides 19 of the latter.

The lever 5 carries a staple-driver 45 which is reciprocable in the throat 24 of the arm 4 to drive the staples *s* into the work. Preferably, the staple-driver 45 is in the form of a relatively thin rectangular blade 46, see Fig. 3, bent at right angles from a strip 46 of hardened sheet-metal which underlies the top 40 of the lever 5 and is fastened thereto by studs 47 and 48 as next described. The studs 47 and 48 also serve as the means for fastening the forward end of a leaf-spring 50 to the under side of the top wall 40 of the lever 5 underlying the driver-strip 46. The forward stud 47 has a knurled head 49 abutting the top of the lever 5 and a reduced shank 51 which is inserted through holes in the driver-strip 46 and the spring 50 and riveted over on the under side of the latter. The knurled head 49 of the stud 47 serves as a means for securing a finger-piece or hollow knob 55 on the top of the lever 5; the knob being preferably molded from plastic in ornamental contour and shouldered at the front to engage the forward end of the lever to prevent it from turning on the stud. It will be observed by reference to Fig. 3 that the spring 50 is offset downwardly at 56 rearwardly of the stud 47 and then offset upwardly to form a boss 57 engaging against the under side of the driver-strip 46, the stud 48 being inserted through holes in the top 40 of the lever 5, the strip 46 and the boss 57 and riveted over at its end. The spring 50 extends rearwardly from the stud 48 with a second offset boss 58 at a slight distance therefrom and then is curved downwardly to adapt its end to engage against the upper edges of the stanchions 10 on the base-plate 6. The spring 50 thus acts to maintain the lever 5 in raised

position relatively to the magazine-arm 4 as shown in Fig. 3, but is adapted to be compressed by forcing the lever downwardly to slide the driver 45 through the throat 24; the rearward end of the spring sliding on the edges of the stanchions 10 during the compression.

The sides 19 of the magazine-arm 4 are cut away at 59 to provide inclined shoulders 60 adapted to be engaged positively by the end of the spring 50 should the arm be raised above the base 2, thereby preventing the return of the lever 5 to operative position until the arm is lowered into adjacent relation to the base. The purpose of this provision is to guard against the accidental driving of a staple should the lever 5 be pressed down toward the arm 4 while the operator's fingers are grasping the under side of the arm.

It will be observed by reference to the drawings that normally the end of the spring 50 bears against and slides on the upper edges of the stanchions 10 at the rearward end of the base 11, either when the parts of the implement are in operative relationship as shown in Fig. 3 or when the lever 5 is unlatched from the magazine-arm 4 and raised into the position shown in Fig. 4 for loading the magazine with staples. However, when the lever 5 is raised above the magazine-arm 4 as shown in Fig. 4, should the arm be inadvertently or accidentally lifted away from the base 11 it will cause the end of the spring 50 to engage positively with the inclined shoulders 60 on the arm. Due to the inclination of the shoulders 60 they will then lie in a plane normal to the flat side of the spring 50 so as to engage positively with its end. Therefore, such positive engagement between the end of the spring 50 and the shoulders 60 on the arm 3 will prevent the lever 5 from being carried back toward the arm until the latter is lowered down against the base 11. Thus, should the operator lift the arm 3 with his fingers thereunder and attempt to connect it with the lever 5, this will be impossible without releasing the spring 50 from the shoulders 60. By this safety provision accidental driving of a staple from the arm 4 into the fingers of the operator held thereneath is prevented so as to avoid possible injury.

The lever 5 normally is retained in cooperative relation to the magazine-arm 4 as shown in Figs. 1 and 2, while permitting it to be pressed down with respect thereto to drive the staples, by an improved latching device next described. The latching means comprises a manually-operative member 65, shown in perspective view in Fig. 6, which is slidably mounted on the under side of the top 40 of the lever 5 in the space above the forward portion of the spring 50, see Figs. 3 and 6. The slide or latch 65 is of inverted channel-shape having a top wall 66 and depending legs or runners 67 abutting the sides 41 of the lever 5. The legs 67 are extended downwardly at the front beyond the sides of the lever 5 and formed with forwardly-projecting hook-like lugs 68 at the bottom. The hooks or lugs 68 are beveled downwardly toward the rear to provide relatively short inclined faces adapted to engage under similar inclined or angular detent-faces 70 at the rearward ends of flanges 71, see Figs. 2 and 4, folded or bent outwardly from the forward ends of the side walls 19 of the magazine-arm 4.

Referring to Figs. 3, 6, and 8, the upper wall of the latch or slide 65 is cut away with a rectangular opening 73 to provide clearance for the boss 57 on the spring 5 and the rivet or stud 48 which fastens the spring in place, whereby to

allow sliding movement of the latch. The top of the latch 65 is also cut away at the front with an opening 74 to adapt it to clear the stud 47 during its sliding movement. The latch 65 is adapted to be manipulated to engage its lugs 68 with or disengage them from the detents 70 on the arm 4 by means of a finger-piece 78 bent upwardly from its rearward end and projecting through a slot 76 in the top of the lever 5.

The latch 65 is mounted rather loosely in the space between the spring 50 and the driver-strip 45 but is controlled in its movement by means of a leaf-spring 80 overlying the top of the lever 5 beneath the hollow knob 55 and fastened thereto by the head of the stud or rivet 48. The fore part of the leaf-spring 80 is offset upwardly to adapt it to overlie the end of a lug 82 bent up from the top of the latch 65 at the rearward end of its opening 74 and projecting through an opening 83 in the top of the lever 5. A rounded protuberance 84 on the forward end of the spring 80 is adapted to engage the edge of the lug 82 to yieldingly retain the latch 65 in forward position with its lugs 68 hooked in under the detents 70 on the arm 4. When it is required to release the latching means to permit raising the lever 5, to uncover the magazine in the arm 4 for supplying it with staples, the latch 65 may be withdrawn by pressing against the finger-piece 78 to force it rearwardly with the spring 80 yielding to allow the lug 82 to ride under the protuberance 84. The method of operation of the complete implement is explained as follows:

After the latching means have been released in the manner described above the cover or lever 5 may be raised from the arm 4 as indicated in Fig. 4 and swung clear back to open the magazine to receive one or more sticks or refills of staples s. To provide for inserting the staples in the magazine the pusher 33 is slid rearwardly therein by the operator's finger to compress the spring 35 and, usually, means such as shown and described in my United States Patent No. 2,264,322 of December 2, 1941, are provided for latching the pusher in retracted position. After the staples have been placed in the magazine the lever 5 is swung down into overlying relation to the arm 4 and the latch 65 is slid forward to engage its hooked lugs 68 under the detents 70.

With the present improved latching means the manual restoration of the parts of the implement to cooperating relationship may be accomplished very conveniently by a simple movement of one hand. With the implement resting on a desk or other support the fingers of one hand are extended from the front across the top of the knob 55 and pressure exerted thereon to depress the lever 5 toward the arm 4. As the lever 5 is lowered to a position slightly below that illustrated in Fig. 2 one finger may be engaged in back of the finger-piece 78 to slide the latch 65 forward to advance its lugs 68 in under the detents 70 for engagement therewith when pressure on the lever 5 is released and the latter is raised by the action of the spring 50. Substantially the same one-handed manipulation may also be used for releasing the latch 65 to permit raising the lever 5 to open the magazine; it being noted, however, that to withdraw the latch it is unnecessary to press down on the lever 5 since the inclined faces of the lugs 68 and detents 70 adapt them to act as cams to effect their release by causing a slight relative movement between the lever and the arm 4.

The implement is operated in the usual manner by inserting the work across the fore part of the

base 2 in under the arm 4 and striking or pressing against the knob 55. The pressure on the knob 55 will first cause both the lever 5 and arm 4 to swing downwardly against the tension of the spring 50 until the forward end of the arm bears against the work resting above the clincher grooves 3. At this juncture the spring 50 will yield to a further extent to allow the lever 5 to continue its descent to slide the staple-driver 45 down through the throat 24. Meanwhile, the foremost staple s in the magazine will have been fed forward across the top of the shear-plate 25 and into the throat 24 to be driven into the work and its legs bent over on the under side thereof by their engagement with the curved bottom of the clincher grooves 3.

In my patent referred to above means are shown for releasing the pusher 33 from its detention means at the rear of the magazine as operated automatically by closing the lever 5 toward the magazine-arm 4 and such means may be employed in the present implement, although they are not herein shown as they form no part of the present invention. The release of the pusher causes it to act continuously to advance the staples progressively in the magazine to feed them one at a time into the throat 24 where they are sheared from the strip or stick and driven into the work by the reciprocation of the driver 45. The implement thus may be operated continuously to apply any desired number of staples to the work while a supply remains in the magazine. When the supply is exhausted the magazine may be loaded again most expeditiously and conveniently in the manner described above.

It will be observed from the foregoing specification that the invention provides improvements in the structure of fastener-applying implements to render them more convenient to operate and more efficient and durable in use. While the invention is herein shown as embodied in a preferred form of device it is to be understood that the improvements may be applied to other types of implements and varied in its details without departing from the spirit and scope of the invention. Therefore, without limiting myself in this respect, I claim:

1. In a device of the type indicated, an arm constructed as a hollow magazine for containing a supply of fasteners, a lever of inverted channel-shape forming a cover for the magazine and pivoted to adapt it to swing relatively thereto to drive the fasteners therefrom, detent-projections on the sides of the arm, and a latch slidable under the top of the arm and formed with depending sides having means for engaging the detent-projections on the arm, said latch having means projecting through the top of the lever for manually sliding it.
2. In a device of the type indicated, an arm of channel-shape forming a hollow magazine for containing a supply of fasteners, a lever of inverted channel-shape pivoted at one end to the magazine-arm to adapt it to rock relatively thereto, means carried by the lever for driving the staples from the arm, a latch slidable within the sides of the lever at the rear of the fastener-driving means and having depending legs with beveled lugs at their forward ends, and detent-projections on the sides of the magazine-arm formed with beveled faces adapted for engagement by the beveled lugs on the lever to connect it with the arm while permitting limited relative movement therebetween.
3. In a device of the type indicated, a hollow

arm constituting a magazine for containing a supply of fasteners, a lever of inverted channel-shape pivoted to swing toward and away from the arm and forming a cover for the magazine, a leaf-spring fastened beneath the top of the lever with its fore part in spaced relation thereto, said spring acting to resist the swinging movement of the lever toward the arm, a U-shaped latch slidably mounted between the spring and the top of the arm and provided with hook-like lugs on its lower forward sides, and detent-projections on the sides of the arm for engagement by the lugs on the latch to limit the upward swinging movement of the lever under the tension of the spring.

4. In a device of the type indicated, a base, a channel-shaped arm pivoted to the base and adapted to contain a supply of fasteners, a lever of inverted channel-shape pivoted to the base to swing relatively to the arm, a leaf-spring for normally rocking the lever upwardly with respect to the arm, said spring fastened beneath the top of the lever and having portions offset downwardly therefrom to provide a space therebetween, a latch having its upper portion slidable in the space between the spring and top of the lever, and detents on the arm engageable by the latch to limit the upward movement of the lever relatively to the arm under the tension of the spring.

5. In a device of the type indicated, a hollow magazine-arm for containing a supply of fasteners, detent-projections at the sides of the arm formed with beveled faces, a lever pivotally mounted at one end to swing toward and away from the arm and forming a closure for its open top, and a latch slidable on the lever and having depending runners formed with forwardly-projecting lugs having beveled faces adapted to engage the beveled faces on the detent-projections to retain the lever in cooperative relation to the arm for driving the fasteners therefrom.

6. In a device of the type indicated, a hollow arm for containing a supply of fasteners, a lever movable relatively to the arm, a driver mounted on the lever for reciprocation across the front of the arm to drive the fasteners therefrom, and a

member having a shear-plate constituted by a flat forward wall with legs projecting rearwardly therefrom and provided with means for riveting it to the bottom of the arm to support the shear-plate in vertical position at the rear of the driver.

5 7. In a device of the type indicated, a hollow arm having a horizontal bottom and upstanding sides for containing a supply of fasteners, said arm having a vertical wall at its forward end, a vertical shear-plate constituted by a flat forward wall disposed in parallel spaced relation to the front wall of the arm to form a throat or guideway for the fasteners, said shear-plate having rearwardly-extending legs of relatively short

10 length with means on their under side for fastening them to the bottom of the arm to support it therefrom, and a driver reciprocable in said throat to drive fasteners therethrough as they are sheared from a strip held in the magazine-arm.

15 8. In a device of the type indicated, a magazine for staples having a bottom and upstanding side walls, said side walls folded inwardly to provide a vertical wall at the forward end of the magazine, and a shear-plate constituted by a flat forward wall disposed at the rear of the front wall

20 25 of the magazine in spaced relation thereto and constructed with integral portions folded rearwardly therefrom to provide longitudinally-extending legs formed with projecting lugs at the bottom engaging openings in the bottom of the arm and fixedly secured therein to mount the shear-plate in the magazine.
